UNITED STATES PATENT OFFICE.

HORST LIEDTKE, OF BERLIN-SCHONEBERG, GERMANY,

MEDICAL SERVICE CABINET.

Application filed August 9, 1923. Serial No. 656,473.

To all whom it may concern:

Be it known that I, Horst LIEDTKE, a citizen of Germany, and resident of Berlin-Schoneberg, Germany, have invented certain new and useful Improvements in Medical Service Cabinets, of which the following is a specification.

My invention relates to improvements in cases for medicines, binding material, and similar matter to be used for giving first medical attendance in cases of accidents, and the object of the improvements is to provide a case of this kind in which the medicines and other matter are readily accessible after unlocking the door. Another object is to provide a case which is equipped with a folding table and a folding roof permitting a surgeon or other attendant to select and prepare binding material and the like without being troubled by bad weather. Other objects of the improvements will appear from the following description.

For the purpose of explaining the invention an example embodying the same has been shown in the accompanying drawings, in which the same reference characters have been used in all the views to indicate corresponding parts. In said drawings,

Fig. 1, is an elevation showing the case open,

Fig. 2, is a similar elevation showing the case half open,

Fig. 3, is a detail sectional view showing parts of one of the door wings and the table,

Fig. 4, is an elevation seen from the left in Fig. 1 and showing the door open.

In the example shown in the drawings, my improved case 17 is provided with two doors 18 adapted to be secured by a lock 19 comprising one or more latch bolts (not shown), connected to a rotary member 21. By turning the arm 32 and the member 21 the door may be unlocked.

Within the case a folding table 22 is hinged at 22^a, and the hinge pintles are disposed a short distance away from the doors 18, so that the table bears (in the closed position of the case) on the doors and tends to open the same. At its ends, the table 22 carries rollers 29 which are adapted to ride on curved guideways 28 provided on the doors 18, as is best shown in Fig. 3. At their lower ends, the said guideways provide a horizontal support 28^a for holding the

table in horizontal position, and the inner ends of the guideways are bent upwardly to provide fingers 30 adapted to engage in cut out portions 31 of the table 22. Thereby the doors are locked in their open positions, and a reliable support is insured for the table. 55 Above the doors 18, a roof 24 preferably of canvas is secured to the case. The sides of the roof are attached to the upper part of the doors. When the doors are closed the roof is folded inwardly, and when opening 65 the doors, the roof is stretched outwardly, as shown in Fig. 2. To the upper parts of the doors, arms 26 are secured, which carry rollers 27 adapted to engage arms 25 hinged to the case at 25^a. When opening the doors, 70 the rollers 27 ride below the hinged arms 25 which now lift the roof 24 so as to stretch the latter, as shown in Fig. 1.

From the foregoing description of the parts, it will be understood that both doors 75 are simultaneously opened by the table 22, and when the doors are in open position, they provide the side walls of a chamber which is covered by the roof 24, so that the medicines and binding material, placed on the table 22 are protected against bad weather. 80

For closing the case, the table 22 is lifted, whereupon the roof is folded and the arms 26 and the rollers 27 release the arms 25. 85

In the example shown in the drawings various boxes 37 and a stretcher 36 are arranged within the case 17.

For placing the stretcher into the case, sleeves 38 are hinged at 39 to the shelf 40 of the case, and these sleeves provide shoes or sockets to receive the handles at one end of the stretcher. To the sleeves springs 41 are attached, and these sleeves are connected also to the rear wall of the case. 95

When out of use, the stretcher is kept within the case with its lower handles supported within the sleeves 38. In order to remove the stretcher, said stretcher is turned downwardly and into horizontal position, in 100 which position the sleeves 38 may be locked against the action of the springs 41 by any suitable means (not shown).

From the foregoing, it is believed that the construction, operation and advantages of 105 the invention may be readily understood by those skilled in the art, and it is apparent that various changes may be made in the

details disclosed without departing from the spirit of the invention as expressed in the claims.

I claim:

- 5 1. A medical service cabinet comprising a case having oppositely swinging hinged doors movable about vertical axes, means for locking said doors in closed position, and a gravity actuated table hinged within the 10 case and arranged to engage and open the doors when the latter are unlocked.
- 15 2. An apparatus of the class described, comprising a case having a hinged door, a table hinged within the case, having a cut out portion and arranged to open the door when the latter is unlocked, a roller on said table, and a guide member secured to said door in position for engagement by said roller and formed at its end with a locking 20 member adapted to engage said cut out portion and hold the door in open position.
- 25 3. An apparatus of the class described, comprising a case having oppositely swinging hinged doors, a table hinged within the case and arranged to open the doors when the latter are unlocked, and a folding roof secured to the case and the upper part of the doors, and adapted to be stretched into

open position when the table actuates to open said doors.

4. An apparatus of the class described, comprising a case having a hinged door, a table hinged within the case and arranged to open the door when the latter is unlocked, a folding roof secured to the case and the upper part of the door, an arm hinged to the case in position for lifting the roof, and a member on said door in position for lifting said arm when opening the door.

35 5. A medical service cabinet comprising a case having oppositely swinging doors movable about vertical axes, a table hingedly mounted within the case and adapted to swing in a vertical plane and open the doors when the latter are unlocked, and a roof secured to the case and to the upper portions of the doors and adapted to be stretched 40 into open position over said table when the latter swings to open the doors.

45 In testimony whereof I hereunto affix my signature in the presence of witnesses.

50 HORST LIEDTKE.

Witness:

E. KUPPIT,
T. Ho' GERM.
